UNITED STATES PATENT OFFICE.

HENRY HELLER, OF NEW YORK, N. Y.

FASTENING DEVICE FOR POCKET-BOOKS.

SPECIFICATION forming part of Letters Patent No. 595,100, dated December 7, 1897.

Application filed June 15, 1897. Serial No. 640,870. (No model.)

To all whom it may concern:

Be it known that I, HENRY HELLER, a citizen of the United States, residing in the city, county, and State of New York, have invented 5 certain new and useful Improvements in Fastening Devices for Pocket-Books, of which the following is a specification.

This invention relates to purses; and its object is to provide a purse with a catch or lock 10 which cannot become accidentally unlocked and the operation of which must be known before the purse can be opened.

The invention consists of a purse provided 15 with a catch, an L-shaped lever pivoted in the frame and provided at one end with a bent portion guided through the hinge-joint and having a push-button at the extremity, a spring-pressed upper arm carrying a loop at its end, and a bent guide-catch.

20 The invention consists, further, of details of construction hereinafter described, and defined in the claims.

Referring to the drawings, Figure 1 is a perspective view of a purse provided with my 25 improved catch. Fig. 2 is an elevation of one part of the purse-frame, showing the details of my improved catch in its locked position. Fig. 3 is a detail view from line 3 3 of Fig. 2, and Figs. 4 and 5 are vertical sections on the lines 4 4 and 5 5, respectively.

In the drawings, B. B' represent the two 35 parts of the hinged frame of a purse provided with open hinge-pivots. To the frame B is pivoted at an L-shaped lever A. The lower arm of the lever is bent at right angles and is guided through the open hinge-pivot and is provided at its extremity with a push-button A'. The upper arm of the lever A is extended along the upper portion of the frame 40 B and is provided at its extremity with a loop C. A suitable leaf-spring a' is secured to the frame B above the upper arm of the lever A and bears thereon, forcing the said arm against the bottom of the angular catch D, which is 45 fixed in the part B of the frame. The loop C of the lever A passes over the upturned end d of the catch D', which is carried by the part B' of the frame.

The operation will be readily understood 50 from the above description.

In order to open the purse, the push-button A' must be pressed, operating the lever A, and forces the upper arm of said lever against the pressure of the spring a'. This 55 action causes the loop C to rise up, releasing

the catch D', when the purse may be opened. Upon closing the purse the spring a' forces the lever A down, and the loop C' again passes over the upturned end of the catch D', thus locking the purse. The opposite side of the 65 frame is provided with a push-button A², secured to the end of a rod A³, which is guided through the open hinge-pivot and bent upward and attached to the side of the frame B. The usual clasp-buttons are provided 65 upon the outside of the frame B B', giving the purse the appearance of having the ordinary fastening common to purses of this kind.

Having thus described my invention, I claim as new and desire to secure by Letters 70 Patent—

1. In a purse, the combination with a two-part hinged frame, having an open hinge-pivot, of a spring-pressed lever pivoted therein and having its lower end guided through 75 the said open pivot, a push-button connected with said lever and located on the outside of said open pivot and a locking-catch fixed in the frame and adapted to be engaged by said lever, substantially as set forth. 80

2. In a purse, the combination with a two-part hinged frame having open hinge-pivots, of a spring-pressed lever pivoted therein and having its lower end guided through the open 85 pivot, a push-button connected with the lower end of said lever and located on the outside of the open pivot, a loop on the upper end of the lever, a guide-catch fixed in the frame, and a locking-catch fixed in said frame and having an upturned end adapted to engage 90 said loop, substantially as set forth.

3. In a purse the combination of the two-part hinged frame having open hinge-pivots, of an L-shaped lever pivoted in said frame and having its lower end guided through the 95 said open pivot and provided with a push-button, a loop on the extremity of the upper arm, a guide-catch fixed in the frame and located back of the said loop, a spring bearing on the upper part of said upper arm and a 100 catch fixed in said frame and provided with an upturned end adapted to receive said loop, substantially as set forth.

In testimony that I claim the foregoing as my invention I have signed my name in presence of two subscribing witnesses.

HENRY HELLER.
